GRINDING MACHINES

Folke Evald Edqvist, 5 Hallspjallsgatan,
Goteborg, Sweden

Filed Apr. 10, 1959, Ser. No. 805,574

Claims priority, application Sweden Nov. 24, 1958

2 Claims. (Cl. 51—45)

The present invention relates to grinding machines of the kind wherein the grinding wheel is movable towards and away from the work piece by means of a piston displaceable in a pneumatic cylinder, a substantially constant air pressure being maintained in one of the cylinder chambers situated on each side of the piston, while the pressure in the second cylinder chamber is adjustable for obtaining the desired grinding pressure between the grinding wheel and the work piece by means of a variable reducing valve connected to a compressed air conduit, said second cylinder chamber communicating with said reducing valve via a two-way valve which by means of an operating valve may be switched from a position in which it connects said second cylinder chamber with said reducing valve to a position in which the cylinder chamber is connected to an outlet.

Grinding machines of this type are used for removing the "casting skin" and glow scales from steel billets and slabs, and for other similar purposes where only the outermost surface layer of the work piece is to be removed together with surface cracks and impurities while maintaining the overall shape of the work piece. To this end the grinding wheel is movable towards and away from the work piece so that it may follow the irregularities in the surface of the work piece. Hitherto known machines of this kind have the drawback, that the grinding pressure varies with changes in position of the grinding wheel caused by irregularities in the work piece surface. Attempts have been made to construct the pneumatic system in such a way, that pressure variations in the above-mentioned cylinder chambers caused by displacement of the piston when the grinding wheel is raised or lowered are balanced as much as possible. However, it has not been possible heretofore to attain sufficient speed and sensitivity of the pressure equalizing devices to keep the grinding pressure constant within the required limits.

This drawback is overcome by the present invention according to which an air tank having considerably greater volume than the pneumatic cylinder is connected to said second cylinder chamber. The pressure variations occurring in the cylinder chamber due to small displacements of the piston will thus be reduced to such an extent, that the grinding pressure may be regarded as practically constant.

According to a preferred embodiment of the invention a valve is arranged between the air tank and said second cylinder chamber communicating therewith, said valve being operable by means of the operating valve in such a way that the connection between the cylinder chamber and the air tank is interrupted simultaneously with the two-way valve being switched to the position connecting the cylinder chamber with said outlet. Due to this arrangement the pressure in the air tank is maintained, so that the machine may be started again without delay.

One embodiment of the invention is illustrated in the accompanying drawings in which:

Fig. 1 is a side view of a grinding machine according

2

to the invention with parts broken away to show the interior of the machine;

Fig. 2 is a partly broken plan view of the machine, and

Fig. 3 is a diagrammatic illustration of the pneumatic system of the machine.

Numerical 1 designates a grinding table provided with clamps 2 for clamping a work piece onto the table. The outline of a steel billet 3 placed between the clamps 2 is indicated in broken lines in Figs. 1 and 2. As indicated at 3' in Fig. 1, the billet may also be placed on edge for grinding the edge surfaces. The grinding table 1 is supported by a machine bed 4 provided on its upper surface with tracks 5 on which the grinding table is displaceable in longitudinal direction. To one side of the bed 4 there is arranged a base structure 6 for a cross slide 7 displaceable along a trackway on top of the base 6 transversely of the grinding table 1. For convenience, the end of the cross slide nearest to the grinding table will here be termed the front end. The cross slide carries at its front end a grinding wheel head 8 which is displaceable vertically for moving the grinding wheel 9 towards and away from the grinding table.

The grinding wheel head 8 is supported by a parallel-linkage arrangement comprising two upper arms 10, 10a and two lower arms 11, 11a. The upper and lower arms are swingably journaled on horizontal shafts 12 and 13, respectively, mounted transversely in the rear portion of the cross slide 7. At their opposite ends, the arms 10, 10a and 11, 11a are passed through slots in the front wall of the cross slide and pivotally connected to shafts 14 and 15, respectively, extending through the grinding wheel head 8. The upper arms 10, 10a are made shorter than the lower arms 11, 11a in order to provide accommodation in the rear portion of the cross slide for an electric motor 16 carried by the arms 10, 10a. The motor is arranged to drive the grinding wheel via the upper shaft 14 of the grinding wheel head 8, said shaft being provided at one end with a number of V-pulleys 17 for V-belts 18 (indicated only in broken lines) passed around a corresponding number of V-pulleys 19 on the motor shaft. To the opposite end of shaft 14 there are attached V-pulleys 20 for V-belts 21 passed around V-pulleys 22 on the shaft of a gear box 23 from which the grinding wheel 9 is driven.

A pneumatic cylinder 24 is disposed in the cross slide 7 adjacent the front end thereof and extends vertically between the arms 10, 10a. The top end of the cylinder 24 is pivotally supported at the top of the cross slide, and the piston rod 25 extending from the lower end of the cylinder is articulated to a cross piece 26 connected to the lower arms 11, 11a. Thus, by raising the cylinder piston the grinding wheel head may be raised. The grinding pressure may also be adjusted by adjusting the air pressure acting on the lower side of the piston, so that the weight of the grinding wheel head is balanced more or less. The pneumatic cylinder is operated from a control stand 27 placed in front of the machine by means of valves and conduits which for the sake of clearness are not shown in Figs. 1 and 2 but which will be described in detail herebelow with reference to Fig. 3.

Fig. 3 is a diagrammatic representation of the pneumatic system of the machine, and to facilitate understanding of the operation of the machine there are also shown the parallel-linkage arms 10, 11 carrying the grinding wheel head. As already mentioned, the piston rod 25 of a piston 28 displaceable in the pneumatic cylinder 24 is coupled to the arms 11, 11a. The cylinder 24 is divided by the piston 28 into two chambers 29 and 30. Compressed air is fed to the chamber 29 of the cylinder 24 from a feed pipe 31 by means of a conduit 32a, a reducing valve 33, a conduit 32b, a valve 34 and a conduit

32c. To the cylinder chamber 30 on the opposite side of the piston 28 air pressure is supplied from pipe 31 by means of a conduit 35a, a reducing valve 36, a conduit 35b, a valve 37 and a conduit 35c. The cylinder chamber 30 communicates with an air tank 40 via a conduit 38a, a valve 39 and a conduit 38b. A branch conduit 41a is further connected to feed pipe 31 and connects to a reducing valve 42 which by means of a conduit 41b is connected to a control valve 43 from which compressed air for opening the valves 36, 37 and 39 is distributed by means of conduits 44, 45 and 46, respectively. Pressure reduction in the valve 36 may be varied by varying the pressure in the control conduit 44. Thus, the valve 36 may be opened and closed by means of the control valve 43 and the air pressure in the outgoing conduit 35b of the valve 36 may be adjusted by adjusting the reducing valve 42 connected in the pressure conduit 41a, 41b leading to the control valve 43. When the control valve 43, which may be operated by means of a pedal 43a, is open the valves 36, 37 and 39 will thus be held open under the action of the pressure in the conduits 44, 45 and 46, respectively, so that compressed air is fed to the cylinder chamber 30 and the air tank 40 communicating therewith. The pressure in the two chambers 29 and 30 of the cylinder may be checked by means of pressure gauges 47 and 48, respectively, and is adjusted by means of the reducing valves 33 and 42, respectively, in such a way that the desired grinding pressure is obtained between the grinding wheel 9 and the work piece. The lower cylinder chamber 29 is provided with a spring-loaded outlet valve 49 which is adjusted in such a way that it will open if the pressure in chamber 29 rises above the desired value. Pressure variations in the chamber 30 caused by displacement of the piston 28 in the cylinder 24 will be very small thanks to the large volume of the air tank 40 connected to said chamber, so that the pressure in chamber 30 may be regarded as practically constant, independently of smaller variations in the position of the piston 28. In spite of the air tank a relatively large pressure variation may occur in chamber 30 if the piston is moved a greater distance upwardly under the influence of irregularities in the surface of the work piece. Such an increase in pressure is balanced by the reducing valve 36 which is provided with an outlet 36b to which the conduit 35b is connected if the pressure for which the valve 36 is adjusted is exceeded a certain amount. Due to the fact that the reducing valve 36 is arranged to be remote-controlled by means of the reducing valve 42 which controls the pressure in the control conduit 44 of the reducing valve 36, the latter may be mounted closely adjacent the cylinder 24, so that equalization of pressure takes place rapidly. The pressure in the cylinder chamber 29 is kept constant by means of the outlet valve 49. The grinding wheel 9 will thus follow all irregularities in the surface of the work piece while maintaining the chosen grinding pressure.

Upon closing of the operating valve 43 the valves 36, 37 and 39 will close, the conduit 35c to the cylinder chamber 30 thereby being connected to an outlet 37a on the valve 37, so that the cylinder chamber 30 will be put into communication with the surrounding air. The pressure in the air tank 40 is maintained since the valve 39 between the cylinder chamber and the tank is closed simultaneously. The grinding wheel 9 will thus be raised

5 rapidly from the work piece as a result of the piston 28 being displaced upwardly under the action of the pressure in the lower cylinder chamber 29. When the arms 10, 11 carrying the grinding wheel head 8 in this way have been swung to an upper end position, a cam 50 mounted on the lower arm 11 will cause the valve 34 to close, so that the compressed air feed to the cylinder chamber 29 is interrupted.

10 The operating valve 43 is also arranged for automatic cut-off in case the grinding wheel is lowered below a certain lowermost level. This cut-off is caused by an air impulse from a valve 51 which is connected to the feed pipe 31 by means of a conduit 52 and to the valve 43 by means of a conduit 53 and arranged to be actuated by a cam 54 movable together with the grinding wheel head and adjustable in vertical direction relative thereto. The air tank 40 is provided with an out-let valve 40a, by means of which the tank may be emptied if needed.

15 20 The invention is not limited to the embodiment herein-before described and as illustrated in the accompanying drawings, said embodiment being susceptible of various modifications with respect to its details, without departing from the spirit of the invention.

25 What I claim is:

30 35 40 45 50 55 1. A grinding machine comprising a support, a driven grinding wheel, means moveably connecting said grinding wheel to said support, a cylinder connected at one end to said support, a piston slideably mounted in said cylinder and dividing said cylinder into a pair of chambers, a rod connected to said piston, extending from the other end of said cylinder and operatively connected to said connecting means for moving the same, a compressed air circuit connected to one chamber of said cylinder for maintaining a constant air pressure in said chamber, a second circuit connected to said first-mentioned circuit and the other of said chambers, a variable reducing valve connected in said second circuit, a two-way valve in said second circuit between said reducing valve and said other chamber capable of admitting air to and exhausting air from said second chamber, an air tank having a considerably larger volume than said cylinder, an auxiliary circuit connecting said second chamber to said air tank, a valve interposed in said auxiliary circuit for controlling the passage of air therethrough, a control valve connected to said compressed air circuit, pneumatic means connecting said control valve to said two-way valve and said auxiliary circuit valve for operating the same together for switching said two-way valve and auxiliary circuit valve from admitting air to said second chamber and between said second chamber and said tank respectively to exhausting air from said second chamber and closing the communication between said second chamber and said tank for controlling the movement of said grinding wheel relative to a work piece.

2. A grinding machine as claimed in claim 1, wherein said reducing valve is positioned adjacent said cylinder and is connected to said pneumatic means for being operated by said control valve.
